DESIGN FOR A HIGHWAY STRADDLE TRUCK

Henry N. Dimick, Portland, Oreg., assignor to
Hyster Company, Portland, Oreg., a corpora-
tion of Oregon

Application October 9, 1944, Serial No. 115,689

Term of patent 14 years

(Cl. D14—3)

To all whom it may concern:

Be it known that I, Henry N. Dimick, a citizen of the United States and a resident of Portland, in the county of Multnomah, State of Oregon, have invented a new, original, and ornamental Design for a Highway Straddle Truck, of which the following is a specification, reference being had to the accompanying drawings, forming a part thereof.

In the drawings:

Figure 1 is a side elevational view of a straddle truck embodying my new design.

Figure 2 is a top plan view of the straddle truck shown in Figure 1.

Figure 3 is a front perspective view of the straddle truck shown in Figure 1.

Figure 4 is a top perspective view of the straddle truck shown in Figure 1.

The characteristic features of my design reside

in the portions shown by means of full lines in the drawings.

The side of the device opposite that shown in Figure 1 of the drawings is substantially the same as illustrated.

I claim:

The ornamental design for a highway straddle truck, as shown and described.

HENRY N. DIMICK.
